UNITED STATES PATENT OFFICE

DENNIS E. SEARS, OF HIGH POINT, NORTH CAROLINA

APPARATUS FOR RAISING SUNKEN VESSELS

Application filed July 28, 1930. Serial No. 471,149.

This invention appertains to ships and more particularly to means whereby a sunken vessel may be readily located and raised.

In accordance with the invention, a strong cable and windlass are mounted upon the vessel, preferably in the hold, a conduit leads upwardly from the hold through the upper deck, a buoy or float rests in a cradle on the upper deck, and a windlass and light rope is mounted on the buoy, the rope being connected to the cable to draw the same to the surface to be utilized for hoisting the sunken ship by a relief vessel.

While the drawing illustrates a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawing hereto attached which is a vertical transverse sectional view of a ship provided with salvage apparatus embodying the invention.

Corresponding and like parts are referred to in the following description and designated in the drawing by like reference characters.

The numeral 1 designates the hull of a ship and 2 the upper deck. In accordance with the invention, a tube or conduit 3 is located at each side of the ship and extends from the bottom through the upper deck. The tubes or conduits 3 taper slightly toward their upper ends and said upper ends flare and curve outwardly and downwardly to prevent the formation of an edge which would tend to fray or injure a cable or line drawn thereover. A windlass 4 is located in the lower end of each of the tubes or conduits 3 and receives a strong and heavy cable 5.

A cradle or framework is mounted upon the upper deck 2 in line with each of the tubes or conduits 3 and receives a buoy or float

6. This cradle or framework embodies uprights 7, a ring 8 connecting the uprights, a band 9 encircling the ring 8 and assisting materially in reinforcing and strengthening the structure, braces 10, a ring 11 connecting the upper ends of the braces 10, and struts 12 connecting the ring 11 with the uprights 7. Braces 13 connect the uprights 7 with the outer ends of the struts 12. The cradle or framework preferably consists of angle bars secured by rivets or bolts as preferred.

The buoy or float 6 is hollow and is formed of sheet metal and tapers from top to bottom. An outer flange 14 at the top of the buoy rests upon the ring 8 within the band 9. A centrally disposed opening 15 extends through the buoy or float 6 and tapers throughout its length. A windlass 16 is mounted within the upper part of the opening 15 and receives a line 17 which is wound thereon. The line 17 consists of a light rope or the like and its lower end is attached in any way to the end of the cable 5. When the buoy or float 6 is in position, the opening 15 thereof is in line with the tube 3. In the event of the buoy or float 6 containing air under pressure, the latter is indicated by means of a gauge 18 fitted to the buoy.

In the event of a vessel equipped with the invention foundering, the buoys or floats 6 are displaced and ride upon the surface of the water. As the vessel sinks, the lines 17 are unwound from the windlasses 16 and serve to anchor the buoys or floats to the submerged vessel. The position of the sunken craft is readily determined by the buoys or floats. The relief ship, after locating the submerged vessel, draws the cables 5 to the surface and utilizes the same as means for raising the vessel. The cables 5, when drawn to the surface, are attached to the hoisting mechanism forming a part of the salvaging apparatus of the relief ship.

Each of the windlasses is mounted in a substantial framework 19 which is attached to the bottom of the vessel. This is essential because the lifting strain, when raising a ship, is applied to the bottom thereof. The cables will be marked at regular intervals to

assure maintaining the vessel on an even keel during the raising operation.

What is claimed is:

1. The combination with a ship, tubes at the sides thereof extending from the bottom through the upper deck, a windlass in each of the tubes, a cable wound upon the windlass, a cradle mounted upon the deck of the ship in line with each of the tubes, buoys for each of the cradles and having a central opening, a windlass in the opening of each buoy, and a line on the windlass passing through the opening in the buoy and the alining tube and connected to the cable.
2. The combination with a ship, a tube at each side thereof extending from the bottom through the upper deck and tapering upwardly and having its upper end flared and of rounded formation, a windlass in the lower end of the tube, a cable thereon, a cradle on the upper deck in line with each of the tubes and comprising upper and lower rings, a tapering buoy having an outer flange at its upper end and a centrally disposed opening, a windlass in the opening of the buoy, and a line on the windlass extending through the opening of the buoy and the beforementioned tube and connected to the cable.

36 In testimony whereof I affix my signature.

DENNIS E. SEARS. [L. S.]
